(74) Attorney, Agent, or Firm—Shlesinger, Fitzsimmons & Shlesinger

(**) Term: **14 Years**

(57) **CLAIM**

The ornamental design for a foam rubber padded fireplace safety cover, substantially as shown and described.

DESCRIPTION

FIG. 1 is a front elevational view of the foam rubber padded fireplace safety cover, the broken line showing of the fireplace is for illustrative purposes only and forms no part of the claimed design;

FIG. 2 is a top plan view thereof;

FIG. 3 is a rear elevational view thereof,

FIG. 4 is a rear elevational view thereof; and,

FIG. 5 is an end view thereof as seen when looking at the right end thereof as shown in FIG. 3, the left end thereof being a mirror image of the right end.
